UNITED STATES PATENT OFFICE.

DENNIS O'LEARY, OF HUBBARD, OHIO.

DESIGN FOR A BLACKING-BOX.

Specification forming part of Design No. 5,118, dated July 11, 1871.

To all whom it may concern:

Be it known that I, DENNIS O'LEARY, of Hubbard, in the county of Trumbull and State of Ohio, have invented a new and Original Design for Blacking-Box; and I do hereby declare that the following is a full, clear, and exact description thereof, which will enable others skilled in the art to make and use the same, reference being had to the accompanying drawing forming part of this specification, in which—

Figure 1 represents a vertical central section of my new blacking-box on the line cc , Fig. 2. Fig. 2 is a top view of the same.

Similar letters of reference indicate corresponding parts.

This invention relates to a new form of blacking-box; and consists in making the same in form

of a saucer with rounded bottom, but with straight vertical sides extending down from the upper edge to form a support.

A in the drawing represents the body of my new blacking-box. It is made in form of a saucer—that is to say, with a rounded bottom and sides, but to its upper edge is secured a vertical flange or rim, a , which extends downward, as shown, and serves as a support for the box, and also to receive the cover B.

I claim as my invention—

The design for the saucer-shaped blacking-box, provided with the pendent flange a , as shown.

DENNIS O'LEARY.
